United States Patent Office

Des. 190,304
Patented May 9, 1961

190,304

AIRPLANE

Charles H. Hurkamp, Hagerstown, Md., assignor to Fairchild Engine and Airplane Corporation, a corporation of Maryland

Filed Feb. 5, 1960, Ser. No. 59,289

Term of patent 14 years

(Cl. D71—1)

FIG. 1

FIG. 2

FIG. 3

FIG. 4

Fig. 1 is a top plan view of an airplane, showing the new design;

Fig. 2 is a front elevational view;

Fig. 3 is a side elevational view; and

Fig. 4 is a rear view.

The dominant features of the design reside in the portion shown in full lines.

I claim:

The ornamental design for an airplane, as shown and described.
